UNITED STATES PATENT OFFICE.

CHRISTIAN WILLIAM MEINECKE, OF JERSEY CITY, NEW JERSEY, ASSIGNOR
TO MEINECKE & CO., OF NEW YORK, N. Y.

DESIGN FOR A BAG FOR ICE OR WATER.

SPECIFICATION forming part of Design No. 34,995, dated August 27, 1901.

Application filed February 12, 1901. Serial No. 47,076. Term of patent 14 years.

To all whom it may concern:

Be it known that I, CHRISTIAN WILLIAM MEINECKE, a citizen of the United States, residing at Jersey City, in the county of Hudson and State of New Jersey, have invented and produced a new and original Design for Bags for Ice or Water, of which the following is a specification.

This invention relates to a new and original design for bags for ice, water, or the like and is illustrated in the accompanying drawings, in which—

Figure 1 is a perspective view, and Fig. 2 a top plan view.

The leading feature of my design resides in a bag having a circular outline with a central mouth or opening and oppositely-located perforated tabs or ears.

In the said drawings the reference-letter *a* indicates the bag, having a circular outline

and a central mouth or opening *b*. Projecting from opposite points of the bag or circumference or located diametrically opposite one another are the tabs or projections *c*, having substantially central perforations *d*. 25

This design presents a bag for ice, water, and the like having a novel, pleasing, and distinctive appearance.

Having thus described my invention, what I claim is—

The design for a bag substantially as herein shown and described.

In testimony whereof I have hereunto set my hand in the presence of two subscribing witnesses.

CHRISTIAN WILLIAM MEINECKE.
